UNITED STATES PATENT OFFICE.

JAMES A. LAWSON, OF TROY, NEW YORK.

DESIGN FOR A HOT-AIR FURNACE.

Specification forming part of Design No. 5,075, dated July 4, 1871.

To all whom it may concern:

Be it known that I, JAMES A. LAWSON, of Troy, in the county of Rensselaer, and in the State of New York, have invented certain new and useful Design for Heating-Furnace; and do hereby declare that the following is a full, clear, and exact description thereof, reference being had to the accompanying drawing making a part of this specification.

Although applicable generally to the entire furnace, as shown in the drawing, my invention applies more especially to the upper portion of the same, in which the side pipes used for connecting the combustion-chamber and upper annular flue are separated from each other by air-

spaces, are arranged radially and vertically with relation to other portions of the furnace, and have their exterior faces constructed in the form of an obtuse angle, substantially as is shown.

Having thus fully set forth the nature of my invention, what I claim as new is—

The design for a hot-air furnace, substantially as shown and described.

In testimony that I claim the foregoing I have hereunto set my hand this 1st day of June, 1871.

JAS. A. LAWSON.
